UNITED STATES PATENT OFFICE.

FREDERICK ZURCHER, OF PITTSBURGH, PENNSYLVANIA.

NECKTIE-CLASP.

1,360,488.

Specification of Letters Patent. Patented Nov. 30, 1920.

Application filed October 3, 1919. Serial No. 328,228.

To all whom it may concern:

Be it known that FREDERICK ZURCHER, citizen of the United States, residing at Bellevue, Pittsburgh, Pennsylvania, in the county of Allegheny and State of Pennsylvania, has invented certain new and useful Improvements in Necktie-Clasps, of which the following is a specification.

This invention relates to a device for attaching a necktie to a collar in such a manner that the tie does not need to be tied each time it is worn. Another object is to provide an improved clasp whereby the portion of the tie which is concealed by the collar is arranged so as to separate the two ends. This is accomplished by means of my improved clasp which when fastened may be drawn back under the collar, thereby giving the tie its proper appearance.

20 A still further object of the invention is to lengthen the wear of the tie, thereby reducing the cost of neckwear to those who use the same.

With these and other objects in view this invention consists of certain novel combinations, constructions, and arrangements of parts, as will be hereinafter fully described and claimed.

25 In the accompanying drawings:

30 Figure 1 is a perspective view of the tie and clasp; Fig. 2 is a detail perspective view of my improved clasp.

Referring to the accompanying drawings by numerals it will be seen that 1 represents the tie. The band portion 2 of the neck portion of the tie passes through the central part of the tie 3, and is adjusted by means of the end 4. In operation the band portion 5 of the tie is placed around the collar so that the clasp portion 6 provided with a button 7 comes out past the end of the col-

lar. The loop 8 is then slipped over the button 7 and the band portion 5 pulled back, carrying the clasp and tie end 9 underneath the collar. Or if a folding collar is in use 45 the clasp portion is brought back from the front of the collar so as to be covered by the wearing apparel.

By referring to Fig. 2 it will be seen that the clasp consists of parts 10 and 11. Part 50 10 is provided with a loop 8 which fits over the button 7. It will be noticed that the clasp is provided with a hinge portion 12 which is operated by means of a spring 13 which holds the teeth 14 of the hinge portion 12 against the teeth 15 of the clasp member 11.

It is obvious that various modifications and changes may be made, and right is reserved to all such as do not depart from the 60 spirit and scope of the invention.

What I claim is:

In a device of the class described, a clasp consisting of two clamping members, a main portion of one of said clamping members 65 provided with teeth at one end and a button at the other end, a hinged member provided with teeth secured to one side of said main portion, a coil spring acting on said hinged portion, a second clamping member provided with teeth at one end and a loop at the other end, a hinged member provided with teeth secured to the main portion, a coil spring acting on said hinged portion, substantially as described for the purpose 70 75 set forth.

In testimony whereof I affix my signature.

FREDERICK ZURCHER.

Witnesses:
